UNITED STATES PATENT OFFICE.

JOSEPH S. B. HARTSOCK, OF WASHINGTON, DISTRICT OF COLUMBIA,
ASSIGNOR TO ROBERT I. GARBER, OF SAME PLACE.

HAT-MARK.

SPECIFICATION forming part of Letters Patent No. 574,325, dated December 29, 1896.

Application filed March 12, 1896. Serial No. 582,906. (No model.)

To all whom it may concern:

Be it known that I, JOSEPH S. B. HARTSOCK, of Washington city, in the District of Columbia, have invented a new and useful Improvement 5 in Hat-Marks, of which the following is a specification.

My invention is in the nature of a simple and cheap attachment designed to be placed in a hat and secured to its sweat-band so as 10 to indicate the ownership of the hat and prevent it from being taken by mistake from the rack or stand on which it may be placed with others.

My invention contemplates not only supplying a visual mark or label with the owner's 15 name on it, but also such a construction and adjustment of the device as will cause it, if placed inadvertently upon the head of a stranger, to prick his forehead and apprise him of 20 his mistake.

It also contemplates the making of the mark or label with double faces, upon one side of which may be placed the name of the dealer from whom it was bought and on the other 25 side the name of the wearer, the idea being to make the device so cheap as to be furnished by the dealer, and bearing his advertisement in the place of the usual label pasted in the crown.

My invention consists in the peculiar construction and arrangement of the hat-mark, which I will now proceed to describe more in detail, reference being had to the accompanying drawings, in which—

Figure 1 is an inside view of a hat with the mark in place and in the position in which the hat is worn. Fig. 2 is a similar view with the mark in the position when off the head and hung upon a rack with others. Fig. 3 is 40 a vertical section through line 3 3 of Fig. 2, showing in dotted lines the position shown in Fig. 1; and Fig. 4 is a sectional detail of a modification.

A represents a body of very thin light metal 45 designed to slip underneath the sweat-band and having at its upper edges two prongs a , which penetrate the sweat-band and are clenched into the same, so that it cannot be lost out. The upper edge of this body-plate 50 is curled over at a' to form a tubular socket for a pintle or hinge-pin c . On this pin is

hinged the folding and reversible label-holder B, containing a card b , on one side of which (see Fig. 1) is printed the advertisement of the dealer and on the other side of which (see Fig. 2) is printed or written the name and, if desired, the address of the owner of the hat. The label-holder is also by preference made of very light thin metal, and its hinged end is curled or rolled into tubular sockets b' b' , which embrace the hinge-pin c , while the middle part is extended in the shape of a tongue b^2 past the hinge-pin and has an offsetting end b^3 , that bears, when the label is up in the position shown in Fig. 1, against a small spring d , secured to the body portion A and extending up beyond and behind the hinge-pin. This spring bears against the tongue b^2 to hold the label firmly in either one of its two positions, and for this purpose said tongue has the projection b^3 on one side and is slightly curved 65 backward from the same. This projection b^3 I prefer to perform by doubling the end of the tongue b^2 on itself to give it stiffness and then bending this doubled end to an offsetting projection. I may, however, modify this construction by bending the tongue into a triangular shape as shown in Fig. 4.

The label-holder B may be of any desired shape, but I prefer to make it circular, as shown. It is stamped out of a piece of thin metal, and the circular card b is retained by a separate ring r of the same size as the main part of the label-holder, and to which it is clamped and held by prongs or spurs t , 80 formed on the edges of said ring and overlapping and clenched upon the ring of the label-holder. On the extreme edge of the label-holder there is also formed, in stamping the same, several sharp-pointed teeth s , which are turned outwardly when the device is in the position shown in Fig. 2, so as to prick 85 the forehead of any one who may inadvertently place the hat upon his head.

In forming my hat-mark it will be seen that 95 the body portion A has its prongs a at its extreme upper edge and bent forwardly and downwardly immediately beside the hinge-pin sockets a' a' , which are also formed of the upper edge of the body portion curled 100 over, as described. As these prongs a connect with the upper edge of the sweat-band

this construction causes the label-holder, when folded down, to descend to a position near the lower edge of the sweat-band, where the label is conspicuous, and the pricking-points are brought near the edge of the sweat-band, where the latter fits tightly against the head, thus insuring attention by the certain action of these points, even if the hat is placed lightly upon or tilted back on the head.

5 10 Having thus described my invention, what I claim as new, and desire to secure by Letters Patent, is—

15 1. A hat-mark comprising a body portion having at its upper edge attaching-prongs bent forwardly and downwardly for connecting directly with the upper edge of the sweat-band and having beside the prongs and immediately adjacent to the same hinge-pin sockets formed of the curled upper edge of 20 the body portion, and a reversible label-holder hinged to said upper edge of the body portion on a level with said prongs and sockets and adapted to fold downwardly in front of the sweat-band near its lower edge and a 25 spring for holding the label-holder to its two positions substantially as and for the purpose described.

2. A hat-mark comprising a body portion adapted for attachment to the sweat-band 30 and having hinged to its upper edge a reversible label-holder provided at its extreme outer or free edge with pricking-points formed

upon the margin of the label-holder substantially as and for the purpose described.

3. A hat-mark comprising a body portion 35 having at its upper edge prongs formed upon the edge of the body portion bent forwardly and downwardly for attachment to the sweat-band and having hinge-pin sockets immediately beside and on the same level as the 40 prongs, a hinge-pin arranged thereon, a label-holder hinged thereupon and having pricking-points formed on the margin of its free or outer edge and a spring for holding the label-holder in its two positions substantially 45 as and for the purpose described.

4. A hat-mark comprising a body portion with prongs a and curled pintle-sockets a' at its upper end, the pintle-pin c , the label-holder B with curled sockets b and b' , tongue b^2 50 and projection b^3 , and a spring d secured to the body portion and bearing against the tongue to hold the label-holder in its two positions as described.

5. A label for a hat-mark comprising a marginal frame with outturned teeth s at its edge, and a ring r with intermediate card b said ring and marginal frame being connected by prongs or clips substantially as shown and described.
